RADIO PILLOW SPEAKER

Arnold R. Dahlberg, Minneapolis, Minn., assignor to
The Dahlberg Company, Minneapolis, Minn., a cor-
poration of Minnesota

Application May 13, 1954, Serial No. 30,476

Term of patent 14 years

(Cl. D26—14)

To all whom it may concern:

Be it known that I, Arnold R. Dahlberg, a citizen of the United States, residing at Minneapolis, county of Hennepin, and State of Minnesota, have invented a new, original, and ornamental Design for a Radio Pillow Speaker, of which the following is a specification, reference being had to the accompanying drawing, forming a part thereof.

Fig. 1 is a view in perspective of a radio pillow speaker, as seen from the front, showing my new design;

Fig. 2 is a view in perspective as seen from the rear;

Fig. 3 is a front elevation; and

Fig. 4 is a side elevation.

I claim:

The ornamental design for a radio pillow speaker, as shown.
